WEATHER STRIP

Filed Nov. 23, 1925

Inventor:
Charles A. Pipenhagen,
By Williams, Bradbury, McCauley & Nunkle
Atty.

UNITED STATES PATENT OFFICE.

CHARLES A. PIPENHAGEN, OF CHICAGO, ILLINOIS.

WEATHER STRIP.

Application filed November 23, 1925. Serial No. 70,750.

The present invention relates to a weather-strip and has particular reference to that type of window weather-strip which is interposed between the sliding sashes in the position generally occupied by the parting bead or strip.

One of the particular objects of the invention is to provide a weather-strip of this type characterized by an improved manner of fastening the weather-strip to the window frame. The present mode of fastening greatly simplifies the mounting of the weather-strip, and avoids the likelihood of deforming the weather-strip in the attaching thereof to the window frame.

Another object of the invention is to provide a weather-strip in which the sealing surfaces will have an increased resiliency or spring for maintaining firm sealing contact with the window, for adapting the strip to different sizes of windows, and for compensating for wear between the sealing surfaces.

Another object of the invention is to provide a weather-strip which will afford the usual line of sealing contact along the side of the sash, and, in addition thereto, will afford a closure or line of sealing along the edge of the sash. This sealing contact at the side and at the edge of the sash greatly increases the effectiveness of the weather-strip for excluding the weather. The resiliency of the weather-strip along the side line of sealing contact and along the edge line of sealing contact also effectively prevents rattling of the window sash in any plane.

In the following description I have described my invention as embodied in different forms of weather-strip designed primarily for sliding sash windows. In view of the fact, however, that certain of the essential features of my invention have wider application to weather-strip and closure strip than to these particular windows, I have drawn some of the appended claims to cover a more general application of these essential features.

In the drawing illustrating the preferred window embodiments:

Fig. 1 is a fragmentary horizontal sec-

tional view through the conventional window having two sliding sashes.

Fig. 2 is a vertical sectional view through the same, taken approximately on the plane 55 of the line 2-2 of Fig. 1.

Fig. 3 is a sectional view on a larger scale of a modified form of window strip, and

Figs. 4, 5 and 6 are similar views illustrating other modifications of my invention.

Referring to Fig. 1, the side rails of a typical sliding sash window are indicated at 11-11, and the two sliding sashes are indicated at 12-12'. The two sashes 12-12' are usually guided in vertical guide channels 14 which are formed on their outer sides by guide strips 15 secured to the window frame. In the usual construction the two sashes are held separated for sliding movement in separate parallel frames by a parting bead or strip which is secured to the rails 11 of the window frame and which projects slightly between the opposing sides of the sashes. This parting bead or strip 75 is not shown, it being supplanted by the present weather-strip. Generally, this parting bead or strip is set into a channel shaped groove or recess 17 formed in the side rails of the window frame, this groove and its 80 associated parting bead usually being of a width substantially equal to the width of the space 18 between the two sashes. In adapting my improved weather-strip to this conventional window construction I utilize 85 the groove 17 for seating a part of the weather-strip.

The present weather-strip is constructed entirely of a single strip of sheet metal, devoid of any rubber surfaces or other material likely to wear or deteriorate. In the particular embodiment shown in Fig. 1 this strip of sheet metal is formed with a channel shaped portion 21 of the proper size to fit into the groove 17. Extending laterally 90 from one side of this channel shaped portion is an attaching flange 22 which is adapted to overlie and bear against the surface of the frame rail 11 along the side of the groove 17. This attaching flange has a plurality of holes 23 therein for receiving the shanks of tacks or nails 24.

From this attaching flange the metal is then doubled back through a curved fold to form a second outer flange 25, which outer flange is spaced slightly from the inner 5 attaching flange 22. This outer flange also has a plurality of holes 26 therein, aligned with the holes 23 in the inner attaching flange, the holes 26 being of sufficient size, however, to pass the heads of either the tacks 10 or nails 24. After the channel shaped portion 21 has been seated in the groove 17, these tacks or nails are centered in the holes 23 and are driven with a punch or other suitable instrument to prevent deforming 15 the outer flange 25, engagement of the heads of these tacks or nails with the inner flange 22 securely fastening the strip to the window frame; the engagement of the channel shaped portion 21 in the groove 17 assists 20 these nails in holding the strip against lateral displacement.

Extending from this outer flange 25, substantially at right angles thereto, is a lateral sealing flange 28. This lateral sealing flange 25 has a rolled or beaded edge 29 which bears 25 against the side of the window sash.

The other side of the channel shaped portion 21 is extended to form another lateral sealing flange 28' which bears against the 30 side of the opposite sash 12'. This flange likewise has a rolled or beaded edge 29.

The flange 25 has considerable resiliency, permitting it to spring towards and away 35 from the flange 22, and this resiliency tends to press this flange 25 against the edge of the sash, thereby affording a line of sealing contact with the edge of the sash, or substantially closing the space which usually exists between the edge of the sash and the 40 window frame. The side sealing flange 28 similarly has considerable resiliency tending to maintain it in firm sealing contact with the side of the window sash. It will be noted that the resiliency of this side sealing flange 45 28 extends through the bowed formation thereof and back through the edge sealing flange 25 to the point of attachment of the fastening tacks with the attaching flange 22, whereby this side sealing flange has additional resiliency tending to prevent it 50 from assuming any set curvature or position out of contact with the sash. The resiliency inherent in the edge sealing flange 25 and in the side sealing flange 28 takes up wear, 55 adapts the weather-strip to windows of different dimensions, and avoids all possibility of the sashes sticking. Also, by fastening the weather-strip to the window frame through the laterally extending attaching 60 flange 22, the difficulty of inserting tacks in the depressed channel portion 21 is avoided, and the side sealing flanges 28-28' can be made with relatively large beaded edges 29 which substantially close the space between 65 these side sealing flanges.

Where the weather-strip is only provided with an attaching flange 22 on one side, as shown in Fig. 1, I prefer to use separate strips for the upper and lower halves of the window and to invert or reverse these strips 70 as shown in Fig. 2. That is to say, when the weather-strips are thus arranged the edge sealing flange 25 for the upper section of weather-strip will engage behind the edge of the upper window sash when this sash is 75 in closed position and the edge sealing flange for the lower section of weather-strip will engage behind the edge of the lower sash when this sash is in closed position. With this arrangement of the two sections of 80 weather-strip the beaded edges 29 of the side sealing flanges 28 will extend in alignment and form a continuous parting bead extending from top to bottom of the window frame. Irrespective of what position the sashes 12 85 and 12' are moved to, they will never pass out of engagement with their respective edge sealing flanges 25. In the modification shown in Fig. 3 the weather-strip is formed with a flat base portion 32 devoid of any 90 channel depression 21. This type of weather-strip may be employed where the window frame has no groove 17 for the parting bead; or it may even be employed where the window frame has such grooves. In this 95 form both sides of the weather-strip may be provided with attaching flanges 22 and with edge sealing flanges 25. Where edge sealing flanges are provided along opposite sides of the strip a single continuous length of strip 100 may be extended from top to bottom of the window frame.

In the modification shown in Fig. 4 the beaded edge of one of the side sealing flanges 28 is formed with a laterally extending 105 flange 33, which contacts with the beaded edge of the opposite sealing flange completely to close the space between these flanges.

In the modification illustrated in Fig. 5 110 the side sealing flanges 28-28' are provided with straight over-lapping flanges 34-34' which completely close the space between these flanges. These closed flanges 34-34' terminate sufficiently short of the outer sides 115 of the side sealing flanges so as not to restrict the lateral resiliency of these sealing flanges.

Fig. 6 illustrates this same arrangement of over-lapping closure flanges in a weather- 120 strip having edge sealing flanges 25 on both sides thereof.

Having thus described my invention, what I claim is:

1. In a weather strip, an integral resilient sheet metal strip, adapted to be substituted for a parting bead, comprising a bottom flange for engaging the bottom of the parting groove, a side flange for engaging the side of said groove, an affixing flange en- 125 130

- gaging the window frame adjacent said groove, and a resilient extension from said affixing flange to effect sealing contact with both edge and side of the sash.
5. 2. In a weather strip, a sheet metal strip comprising an attaching flange, an edge contact flange bent back adjacent said attaching flange, and a side sealing flange extended transversely from said edge contact flange.
10. 3. In a weather strip, a sheet metal strip comprising an attaching flange, an edge contact flange bent back adjacent said attaching flange, and a side sealing flange extended transversely from said edge contact flange, said edge contact flange having apertures to pass heads of securing means.
15. 4. In a weather strip, means for resilient engagement with the edge of a window, means for resilient engagement with the side of a window, said means being joined at the corner of said window and a securing flange substantially parallel to said first means.
20. 5. In a weather strip, means for resilient engagement with the edge of a window, means for resilient engagement with the side of a window, said means being joined at the corner of said window, a securing flange substantially parallel to said first means and an aligning flange extending into the parting groove of a window frame.
25. 6. A resilient parting bead comprising a box-like portion adapted to fit a parting groove, and side and edge sealing flanges extending therefrom.
30. 7. A resilient parting bead comprising a box-like portion adapted to fit a parting groove, side and edge sealing flanges extending therefrom and an attaching flange to fit the window frame adjacent said groove.
35. 8. The combination with a window frame and sash, of a weather-strip comprising an attaching flange extending from one side thereof, a closure flange folded back over said attaching flange, said flanges having aligned openings therein, the openings in said closure flange being larger to pass the heads of attaching nails, a side sealing flange extending from said closure flange for contacting with the side of the sash, and a second side sealing flange extending from the opposite side of said weather-strip.
40. 9. The combination with a window frame and sash, of a weather-strip comprising a channel portion adapted to be received in the parting bead groove of the window frame, a first flange extending laterally from said channel shaped portion, a second flange folded back over said first flange and spaced therefrom, and a third flange projecting from said second flange in position to engage the side of the window sash.
45. 10. The combination with a window frame and sash, said window frame having a groove for receiving the parting bead, of a weather-strip comprising a channel shaped portion to fit into said groove, an attaching flange extending laterally from said channel shaped portion, a closure flange folded back over said attaching flange, a side sealing flange extending from said closure flange for contacting with the side of the window sash, and a side sealing flange extending from the opposite side of said channel shaped portion.
50. 11. The combination with a window frame and sash, said frame having a groove therein for receiving a parting bead, of a weather-strip comprising a channel shaped portion for engaging in said groove, an attaching flange extending laterally from one side of said channel shaped portion, an edge sealing flange folded back over said attaching flange and spaced therefrom, said flanges having aligned openings therein, the openings in said edge sealing flange being sufficiently large to pass the heads of attaching nails driven through the holes in said attaching flange, a side sealing flange extending from said edge sealing flange, a beaded edge on said side sealing flange, a side sealing flange extending from the opposite side of said channel portion, and a beaded edge on said second side sealing flange.
55. 12. A resilient parting bead comprising a box-like portion adapted to fit a parting groove, and side and edge sealing flanges extending therefrom, said flanges meeting in resilient contact.
60. 13. In a weather strip, a parting bead having means to effect resilient edge contact, means to effect resilient side contact and means to effect resilient contact with the parting bead rabbet of a sash.
65. 14. In a weather strip, a parting bead having means to effect a resilient edge contact, means to effect resilient side contact and means to close the opening between said first named means.
70. 15. The combination with a window frame and sashes, of a weather-strip comprising a pair of flanges adapted to effect sealing contact with the sides of the window sashes, said sealing flanges having beaded edges, and a flange extending from one of said beaded edges for engaging with the other of said beaded edges.
75. 16. The combination with a window frame and sashes, of a weather-strip comprising a pair of sealing flanges adapted to contact with the sides of the window sashes, and over-lapping flanges extending from said sealing flanges for closing the space therebetween.
80. 17. The combination with a window frame and sash of a weather-strip adapted to be substituted for the parting bead and comprising resilient flanges effecting seal.

ing side contact with the said sash and a closed outer edge.

18. The combination with a window frame and sash of a weather-strip adapted to be substituted for the parting bead and comprising a resilient member with its edges brought into sealing contacting relation to form a closed channel.

19. A weather strip comprising a closed resilient channelled member formed by 10 bending edges to meet in sliding resilient contact.

In witness whereof, I hereunto subscribe my name this 18th day of November, 1925.

CHARLES A. PIPENHAGEN.
